BALL GAME APPARATUS

John Comoletti, Los Angeles, Calif.

Application March 20, 1939, Serial No. 262,838

2 Claims. (Cl. 265—20)

This invention relates generally to amusement devices and more particularly to games of skill embodying targets at which suitable projectiles are adapted to be directed by the players to score points in accordance with the degree of success of the players in striking the targets with the projectiles.

An object of the invention is to provide a game apparatus embodying targets mounted to move when struck by a projectile, and in accordance with the force and direction imparted to the projectile by a player, this operation being preferably, although not necessarily, in conjunction with indicators which are operatively associated with the targets in a manner to indicate the amount of movement of the respective targets and thus enable the most skillful players to be determined.

Another object of the invention is to provide a game apparatus of the above described character in which the targets are mounted to rotate when struck by a projectile and are operatively associated with devices which register the number of revolutions of the targets.

A further object of the invention is to provide a game apparatus in which the targets can be quickly brought to rest from oscillating motion following rotational motion of the targets by projectiles, and the registering devices are conveniently resettable for the start of another game.

With these and other objects in view, the invention resides in the combinations and arrangements of elements as set forth in the following specification and particularly pointed out in the appended claims.

In the accompanying drawings,

Figure 1 is a view in front elevation, partly in section, of one of a number of identical targets which are provided in the ball game apparatus embodying this invention;

Figure 2 is a view of the target in side elevation;

Figure 3 is a vertical sectional view taken on the line 3—3 of Figure 1;

Figure 4 is a plan view showing dial portions of the indicating and registering mechanisms operatively associated with the targets;

Figure 5 is a plan sectional view of the indicating and registering mechanism provided for each target;

Figure 6 is a vertical transverse sectional view of the game apparatus;

Figure 7 is a diagrammatic view of electrical circuits comprised in the game apparatus shown in the preceding figures.

Referring specifically to the drawings, and par-

ticularly to Figures 1 to 7, inclusive, this form of the invention comprises a suitable table 10 closed at the front thereof by a vertical wall 11 along which players can stand side by side in front of a corresponding number of targets T, a typical one of which is shown as being mounted on the table 10 at a location sufficiently remote from the front wall thereof to require skill on the part of the players to strike the targets with suitable projectiles such as balls B, with equal numbers of which the players are provided at the start of a game.

Operatively associated with each target T and mounted in the top of the table 10 adjacent the front wall 11 so as to be conveniently viewed by the respective player, is an indicating and registering device designated generally at R, which device is operatively associated with the target in a manner to be hereinafter described.

Each target T comprises a suitable target figure 12 of any nature, which is fixed to a shaft 13 journaled at its reduced ends in bearings 14 supported in spaced uprights 15 of a U-shaped bracket or support 16, the base of which is rigidly secured by screws 17 or other fastening means to the top 20 of the table 10.

Fixed to the shaft 13 by screws 18 are counterweights 19 which tend to maintain the figure 12 in a perpendicular position. One of the counterweights is provided with a lug 20 which broadly constitutes a means for momentarily closing a switch S during each revolution of the figure 12.

The switch S is composed of resilient contact arms 21 and 22 insulated from each other and fixed to one of the uprights 15, with the contact arm 21 disposed to be flexed by the lug 20 into engagement with the contact arm 22 by a wiping or camming motion of the lug against said contact arm.

The momentary closing of the switch S during each revolution of the figure 12 effects actuation of the respective one of the devices R, each of which comprises a base plate 25 on which is rotatably mounted a shaft 26 having fixed thereto a pointer 27 adapted to co-act with suitably numbered graduations 28 of a dial 29 which is mounted in the top of the table 10 so as to be readily viewed by the player.

Also fixed to the shaft is a feed member in the form of a ratchet wheel 30, the teeth of which 50 are engaged by a gravity feed pawl 31 pivoted at 32 on an arm 33 pivoted at 34 on the plate 25 and normally urged to one extreme position by a spring 35.

The core 36 of a feeding solenoid 37 is pivotally 55

connected at 38 to the arm 33 for co-action therewith in retracting the feed pawl 31 against the action of the spring 35, upon momentary closing of the switch S, which operation supplies current from a suitable battery 39 to the winding of the solenoid through conductors 40 and 41 with which the contact arms 21 and 22, the battery and the solenoid are in series as is shown in circuit diagram of Figure 7. Upon de-energizing of the solenoid 31 as a result of opening the switch S, the spring 35 will advance the feed pawl 31 sufficiently to rotate the ratchet wheel through an angular distance corresponding to the spacing of the graduations 28 of the dial 29 to indicate thereon one revolution of the target figure 12.

Operating in conjunction with the feed pawl 31 is a holding pawl 42 carried by an arm 43 pivoted at 44 on the plate 25 and maintaining the holding pawl in engagement with the teeth of the ratchet wheel 30 by means of a spring 45, whereby to prevent retrograde movement of the ratchet wheel by a coil spring 46 which is fixed at one end to the wheel and at its other end to the plate 25 so as to constantly tend to effect said movement of the wheel to a starting position definitely determined by a stop pin 47 on the wheel, engageable with a stop lug 48 on the plate 25.

A resetting solenoid 49 is fixed to the plate 25, and the core 50 of the solenoid is pivotally connected at 51 to the arm 43 for co-action therewith when the solenoid is energized, to cause a pin 52 on a lateral extension 53 of the arm 43 to engage the feed pawl 31 and clear the latter from the teeth of the ratchet wheel 30 so that the coil spring 46 will be free to act and restore the pointer 27 to the aforeslated starting position.

Energization of the resetting solenoid is effected by a suitable push button switch S', the terminals of which are in series with the winding of the solenoid 49 and the battery 39 through the conductor 41 and conductors 55, 56 and 57.

An electromagnet 60 is supported in one of the uprights 15 of the support 16 with the core 61 of the electromagnet disposed to magnetically attract one of the weights 19 which forms an armature therefor, upon manual closing of a suitable push button switch S2 with the terminals of which the winding of the electromagnet and the battery 39 are in series through the conductors 41 and 57 and conductors 62, 63 and 64. Thus, it will be clear that any prolonged oscillatory movement of the target figure 12 following its rotational movement can be arrested, and the target figure 12 immediately brought to rest by a manual closing of the switch S.

In the operation of the game apparatus above described, it will be clear that upon striking the

target figure 12 with a ball B, the impact of the latter upon the figure will react to rotate the figure to a greater or lesser extent depending on the momentum of the ball and the distance from the axis of the shaft 13 at which the ball strikes the figure, thus actuating the respective device R for its pointer 27 to indicate the number of revolutions made by the target figure. With a number of persons playing the game by throwing an equal number of balls at the respective target figures of the apparatus, the most skillful of the players as determined by that one of the devices R registering the greatest number of revolutions will be the winner of the contest.

What is claimed is:

1. In a game apparatus, a target figure; means including a shaft mounting said figure for rotation about a fixed axis to normally occupy a position for striking by a projectile; a counting mechanism; a feeding mechanism including a feed wheel driving the counting mechanism, and a feed member for advancing said wheel; means normally urging the counting mechanism to a starting position; means including a holding member co-acting with the feed wheel to prevent retrograde movement of the counting mechanism; a circuit including a source of current supply, a switch and a solenoid operatively connected to said feed member to actuate the latter and advance the counting mechanism; a solenoid operatively connected to the holding member; an operative connection between the feed and holding members by which energization of the second said solenoid to release the holding member from the feed wheel will release the feed member therefrom; and a circuit including the second said solenoid, a source of current supply and a switch.

2. In a game apparatus, a target figure; means mounting said figure for movement about a fixed axis to rotate when struck by a projectile; a revolution indicator; a feeding mechanism operatively connected to said revolution counter to drive the latter; an electrical circuit including a source of current supply, a switch and a solenoid operable when energized to actuate the feeding mechanism and cause the counting of a revolution by said counter; means rotatable with the target figure, and operating to close said switch momentarily during a revolution of the figure; means co-acting with the target figure and tending to maintain the latter in a position for striking by a projectile; and electromagnetic means co-actable with the figure to bring same to rest following its rotation, upon energization of the electromagnetic means.

JOHN COMOLETTI.
